CLAIM

The ornamental design for an equipment trailer, as shown and described.

DESCRIPTION

FIG. 5 is a front elevational view of the equipment trailer; and

FIG. 6 is a rear elevational view of the equipment trailer.
